UNITED STATES PATENT OFFICE.

JOSEPH S. ISIDOR, OF NEWARK, NEW JERSEY, ASSIGNOR TO THE R. NEUMANN HARDWARE CO., A CORPORATION OF NEW JERSEY.

BAG-FRAME LOCK.

1,405,919.

Specification of Letters Patent. Patented Feb. 7, 1922.

Application filed October 7, 1920. Serial No. 415,269.

To all whom it may concern:

Be it known that I, JOSEPH S. ISIDOR, a citizen of the United States, residing at Newark, in the county of Essex and State of New Jersey, have invented certain new and useful Improvements in Bag-Frame Locks; and I do hereby declare the following to be a full, clear, and exact description of the invention, such as will enable others skilled 5 in the art to which it appertains to make and use the same, reference being had to the accompanying drawings, and to characters of reference marked thereon, which form a part of this specification.

15 This invention relates, generally, to improvements in frames for travelling bags, and the like, and locking devices therefor; and, the present invention has reference, more particularly, to a novel and simply 20 constructed lock secured to the usual outer frame-section of the bag-frame, said lock being provided with a frame-section engaging member or members, which are arranged and constructed in a manner, so as 25 to readily co-operate with correspondingly disposed openings formed in the inner frame-section of the bag-frame, to retain the said hinged frame-sections in their closed relation.

30 As is well-known, in the construction of bag-frames, two hinged or pivotally connected frame-sections are employed, the inner frame-section being quite narrow, and that the said narrow frame-section may be 35 provided with lock-post receiving openings which are centrally disposed between the longitudinally extending marginal edges of said inner frame-section, the novel bag-frame lock hereinafter more fully described 40 has been devised.

The present invention, therefore, has for its principal object to provide a novel and simply constructed bag-frame lock of the character hereinafter set forth; and, further- 45 more, to provide, in connection with such lock, the narrow inner frame-section of the bag-frame with lock-post receiving openings which are centrally disposed between the longitudinally extending marginal edge-

50 portions of the frame-section, that the said narrow frame-section is not weakened, and, also, that the said frame-section has a continuous unbroken marginal edge, so as to provide a neater construction of frame, and 55 enabling the omission of the usual hasps se-

cured to the narrow inner frame-section by being riveted thereto.

It will be understood, that by the omission of the usual hasps, the cost of manufacture is greatly reduced; but, aside from this fact, the frame-sections have unobstructed marginal edge-portions, thus, when the bag has been opened, presenting no objectionable obstructions in which the lace on the sleeves of ladies' garments, when the hand is thrust into the bag, can catch and become torn.

Other objects of the present invention not at this time more particularly enumerated, will be fully understood from the following 70 detailed description of the present invention.

With the various objects of the present invention in view, the said invention consists, primarily, in the novel bag-frame lock hereinafter more fully set forth, and the said invention consists, furthermore, in the novel arrangements and combinations of the various devices and parts, as well as in the details of the construction of the said parts, 80 all of which will be more fully described in the following specification, and then finally embodied in the clauses of the claims which are appended to the said specification, and which form an essential part of the same. 85

The invention is clearly illustrated in the accompanying drawings, in which:

Figure 1 is a top face view of fragmentary portions of the outer and inner frame-sections of a bag-frame provided with a lock 90 made according to and embodying the principles of the present invention, the parts being represented in their closed relation.

Figure 2 is a similar representation of said portions of the outer and inner frame-sections, the latter being represented in their unlocked or opened relation; and Figure 3 is a bottom view of the said frame-sections and the lock.

Figure 4 is an inner face-view or elevation of the outer frame-section and the lock secured thereto, said view being represented as looking toward the frame-section in the arrow X in said Figure 2.

Figure 5 is a transverse vertical sectional 105 representation of the outer and inner frame-sections in their closed relation and of the lock secured to the outer frame-section, said section being represented as being taken on a plane through line 5—5 in Figure 4, look- 110

ing in the direction of the arrow Y, and showing the lock-post of the lock in its holding or retaining engagement with the inner frame-section.

5 Similar characters of reference are employed in all of the said above described views, to indicate corresponding parts.

Referring now to the several figures of the drawings, the reference-character 1 indicates 10 a fragmentary portion of the outer frame-section, and 2 a similar portion of the inner frame-section of a bag-frame, said frame-sections being, preferably, right-angled in cross-section, as indicated more particularly 15 in Figure 5 of the drawings. As indicated, the outer frame-section 1 is formed with the usual key-box receiving opening 3, and the said narrow inner frame-section 2 is provided with a pair of lock-post receiving 20 openings 4, centrally disposed between the longitudinally extending marginal edge-portions of the frame-section 2, as represented in Figures 2, 3 and 5 of the drawings, and preferably of the configuration shown in 25 said Figures 2 and 3.

The complete structure of lock which is shown more particularly in Figures 3 and 4 is indicated by the reference-character 5, and the same comprises a top-plate 6, 30 adapted to be secured against the lower face-portion 7 of the outer frame-section 1, as is shown in Figures 3 and 4, by means of rivets 8, but which may be secured to said frame-section in any other suitable 35 manner, as will be clearly understood. Suitably secured to said top-plate 6 is a suitably formed shell or casing, comprising a bottom-plate 9 and vertical face-plate 10, provided with openings 11 which are arranged in a manner, substantially as illustrated in Figures 4 and 5 of the drawings. The general arrangement and construction 40 of the lock-mechanism contained in said shell or casing is of the usual construction, and need not, therefore, as to its details 45 be described. Suitably secured to and extending upwardly from the above-mentioned bottom-plate 9 are a pair of posts, as 12, each post being encircled by a coiled spring 50 13. The upper end-portion of each post 12 is provided with a suitable enlargement or head, as 14, said heads acting as stops to limit the usual upward movement of a bridge-piece or element 15 which is mov- 55 ably disposed upon said posts, and which rests upon the upper free ends of the said springs 13. Connected with the said bridge 60 15, and secured thereto in any suitable manner, is a plate 16 which is provided with laterally projecting fingers or other suitably 65 formed members, as 17, and which extend into and through the previously mentioned openings 11 in the vertical face-plate 10 of the lock-casing or shell, as will be clearly understood from an inspection of Figures

3, 4 and 5 of the drawings. Each finger 17 is also provided with an upwardly projecting frame-section engaging lock-post or stud 18, each post 18 being formed with an arc-shaped or other suitably formed marginal edge, as 19, so that, when the inner frame-section 2 is brought into its closing relation within the outer frame-section 1, the said edges 19 of the posts or studs 18 will ride against the marginal edge-portions 20 of said frame-section 2, thereby depressing the various parts against the action of the spring 13, until brought directly beneath the lock-post receiving openings 4 in the frame-section 2, into which the said 25 posts or studs 18 are forced by the action of the springs 13, the vertical marginal edge-portions 21 of said posts or studs 18 engaging the marginal edge-portions 22, which partially bound the openings 4, so 30 as to thereby positively maintain the closed relation of the two frame-sections, as will be clearly evident from an inspection of said Figure 5 of the drawings.

The usual combined key-box and finger-piece of the lock, for depressing the bridge 15, and the parts connected therewith, is indicated by the reference-character 23, said combined key-box and finger-piece extending upwardly into and through the hereinabove mentioned receiving opening 3 with which the frame-section 1 is provided.

The above-stated arrangement of the frame-engaging fingers or lock-posts 18 to one side of the spring-controlled bridge 100 of the lock-mechanism permits of the arrangement of the receiving openings 4 to be centrally located in the narrow inner frame-section 2, with relation to the width of said narrow frame-section, so that the 105 said frame-section is not thereby weakened. Furthermore, with a lock-mechanism, provided with lock-posts or frame-engaging fingers located to one side of the usual spring-controlled bridge, instead of upon 110 the said bridge, as heretofore, the usual hasps, riveted to the said frame-section 2 and projecting beyond the marginal edge of said frame-section, may be and are entirely omitted, thereby not only cheapening the 115 cost of construction, but doing away with obstructing projections, in which garments may catch and become torn.

Of course, I am fully aware that changes 120 may be made in the general arrangements and combinations of the several devices and parts, as well as in the details of the construction of the said parts, without departing from the scope of the present invention 125 as set forth in the foregoing specification, and as defined in the clauses of the claims which are appended thereto. Hence, I do not limit my present invention to the exact arrangements and combinations of the several devices and parts as described in the 130

said specification, nor do I confine myself to the exact details of the construction of the said parts, as illustrated in the accompanying drawings.

5 I claim:—

1. In combination with the outer and inner frame-sections of a bag-frame, said inner frame-section having a non-obstructed longitudinally extending marginal edge and being provided with a receiving opening located back of said longitudinally extending marginal edge of said inner frame-section, a bag-frame lock mounted upon the inner surface of said outer frame-section, a bridge-plate movably disposed the shell of said lock, and means connected with and extending laterally from said bridge-plate adapted to enter the receiving opening in said inner frame-section, for maintaining a closed relation of said frame-sections.

2. In combination with the outer and inner frame-sections of a bag-frame, said inner frame-section having a non-obstructed longitudinally extending marginal edge and being provided with a receiving opening located back of said longitudinally extending marginal edge of said inner frame-section, a bag-frame lock mounted upon the inner surface of said outer frame-section, a spring-actuated bridge-plate movably disposed the shell of said lock, and means mounted with and extending laterally from said bridge-plate adapted to enter the receiving opening in said inner frame-section, for maintaining a closed relation of said frame-sections.

3. In combination with the outer and inner frame-sections of a bag-frame, said inner frame-section having a non-obstructed longitudinally extending marginal edge and being provided with lock-post receiving openings located back of said longitudinally extending marginal edge of said inner frame-section, a bag-lock mounted upon the inner surface of said outer frame-section, said lock comprising a shell formed in one of its sides with openings, a bridge-plate movably disposed within said shell, fingers connected with and extending laterally from said bridge-plate and through the openings in said shell, and frame-section engaging posts or studs upon said fingers, said posts or studs being adapted to enter the lock-post receiving openings in said inner frame-section,

tion, for maintaining a closed relation of said frame-sections.

55

4. In combination with the outer and inner frame-sections of a bag-frame, said inner frame-section having a non-obstructed longitudinally extending marginal edge and being provided with lock-post receiving openings located back of said longitudinally extending marginal edge of said inner frame-section, a bag-lock mounted upon the inner surface of said outer frame-section, said lock comprising a shell formed in one of its sides with openings, a spring-actuated bridge-plate movably disposed within said shell, fingers connected with and extending laterally from said bridge-plate and through the openings in said shell, and frame-section 60 engaging posts or studs upon said fingers, said posts or studs being adapted to enter the lock-post receiving openings in said inner frame-section, for maintaining a closed relation of said frame-sections.

65

5. In combination with the outer and inner frame-sections of a bag-frame, said inner frame-section having a non-obstructed longitudinally extending marginal edge and being provided with lock-post receiving 70 openings located back of said longitudinally extending marginal edge of said inner frame-section, a bag-lock mounted upon the inner surface of said outer frame-section, said lock comprising a shell having a bottom-plate and a vertical side-plate, said side-plate being provided with openings, posts connected with and extending vertically from said bottom-plate, springs encircling 75 said posts, a bridge-plate movably disposed upon said posts, fingers connected with and extending laterally from said bridge-plate and through the openings in said side-plate of the shell, and a frame-section engaging lock-post or stud upon each finger adapted 80 to enter the lock-post receiving openings in said inner frame-section, for maintaining a closed relation of said frame-sections.

75

85

In testimony, that I claim the invention set forth above I have hereunto set my hand 100 this 28th day of September, 1920.

JOSEPH S. ISIDOR.
